UNITED STATES PATENT OFFICE.

DAVID J. CARSON, OF BUFFALO, AND JAMES A. LANIGAN, OF LANCASTER, NEW YORK.

JOURNAL-BOX.

1,112,118.

Specification of Letters Patent. Patented Sept. 29, 1914.

Application filed June 18, 1912. Serial No. 704,346.

To all whom it may concern:

Be it known that we, DAVID J. CARSON, a subject of the King of Great Britain, residing at Buffalo, in the county of Erie and 5 State of New York, and JAMES A. LANIGAN, a citizen of the United States, residing at Lancaster, in said county and State, have invented a new and useful Improvement in Journal-Boxes, of which the following is 10 a specification.

This invention relates to journal boxes for railway rolling stock, and more particularly to journal boxes of the sort which are provided with spring-operating devices for 15 holding the box lids in both their open and closed positions.

In the various types of boxes heretofore made, which have been constructed with the particular object in view of holding the 20 lid securely closed so as to prevent the entrance of foreign matter into the box and also to prevent the rattling of the lid, the general Master Car Builders' features have been partly or wholly disregarded. By reason of this at each junction point the railroads must necessarily carry in stock for repair purposes not only the usual Master Car Builders' lids, but also suitable lids for 25 each of the various different special constructions used, thus greatly increasing the expense and, therefore, making their use impractical.

The object of this invention is to provide 30 a journal box with a spring holding device which can be economically manufactured and which will securely hold the lid in both 35 its open and closed positions, and further to so construct and arrange the several parts that the lid, if lost or damaged, can be 40 readily replaced by a lid of the standard Master Car Builders' type.

In the accompanying drawings, consisting of two sheets: Figure 1 is a front elevation of a journal box embodying the invention. Fig. 2 is a fragmentary side elevation thereof. Fig. 3 is a fragmentary plan view of the journal box. Fig. 4 is a fragmentary sectional elevation in line 4—4, Fig. 3, showing the lid in its open position. Fig. 5 is a 45 fragmentary front elevation, partly in section, showing the lid in its open position. Fig. 6 is a front elevation of the box with a Master Car Builders' lid secured in place 50 thereon. Fig. 7 is a fragmentary side elevation thereof. Fig. 8 is a fragmentary side elevation in line 8—8, Fig. 6.

Like reference characters refer to like parts in the several figures.

A represents the body or casing of a journal box which in its general form and dimensions is of the standard Master Car Builders' type, which is provided at its front or outer end with the usual opening a, through which access is afforded to the journal and bearings, and b represents the 60 usual hinge lug with which standard journal boxes of the Master Car Builders' type are provided.

A cover or lid C is provided for closing the opening a. This lid in the construction shown is provided at the opposite sides of its upper end with lateral trunnions c, preferably integral therewith, which are seated in bearings D on the box A and constitute pivots on which the lid swings when being 65 opened and closed. By providing the lid with integral trunnions the number of detachable parts of the box is greatly reduced and the use of bolts and keys may thus be entirely eliminated. The bearings D are 70 located at opposite sides of the top of the box A and preferably consist of hook shaped lugs which are formed integrally with the box. If desired, the ends of the lugs may be bent downwardly somewhat in the rear of 75 the trunnions c to retain the latter in the bearings. The ends of the lugs can be bent upwardly again to release the trunnions and permit the lid to be detached. Bearings 80 of any other suitable construction, however, 85 may be employed, if desired.

E represents suitable springs which are provided for retaining the lid C in its open and closed positions. In the construction shown these springs are formed of flat 90 spring material and are of V-shape. They are arranged on the upper face of the box at the opposite ends of the lug b and are preferably of sufficient width to fill the space between the ends of the lug and the bearings 95 D, and are thus held from lateral movement on the box. One arm of each spring rests upon and is secured to the upper face or top of the box, while the other arm extends upwardly therefrom at an inclination thereto. 100 Rivet studs e, formed on the upper face of the box as shown, or any other suitable means may be employed for securing the springs to the box. The inclined free arms of the springs E are adapted to engage cam 105 projections F formed on the upper edge of the lid C, and hold the lid normally in its 110

closed position. When the lid is raised, the projections F ride upon the upper faces of the inclined spring arms and further compress the springs, and when the lid is in its open position, the cam projections of the lid stand at such an angle to the inclined arms of the springs, that the pressure of the springs thereon tends to hold the lid in this position.

10 The actual movement of the springs under the action of the cam projections, as the lid is raised and lowered, is very slight and the springs can, therefore, be made sufficiently stiff and firmly hold the lid in both its open and closed positions. When the lid is in its closed position, the springs bear on the cam projections of the lid with a greater leverage than when the lid is raised and thus the more securely hold the lid closed and prevent it from rattling or accidentally becoming open. While the construction and arrangement of the springs, as shown, is preferred as being simple, economical and durable, springs of any 15 other suitable construction may be employed for this purpose and arranged on the box in any suitable manner.

Inwardly extending flanges G are provided on the under or inner side of the lid C, preferably integral therewith, which embrace the side edges of the opening a in the casing A, thereby effectually excluding all foreign matter which might otherwise gain entrance to the bearings. The lid is preferably provided with an integral pocket or hollow portion H adapted to receive and inclose the hinge lug b. The lug b, therefore, does not interfere with the movement of the lid, and the pocket protects the lug from damage and also prevents water and dust from entering the box. The lid thus forms a tight closure for the box, and is held by its springs securely closed, so as to prevent dirt and other foreign matter from finding its way into the box. Should the lid C become damaged, it can be readily removed and quickly and easily replaced by a standard Master Car Builders' lid, as shown in Figs. 6, 7, and 8, in which figures, I represents a lid of the standard Master Car Builders' type which is secured to the hinge lug b on the box A by means of the usual bolt i and cotter pin j. The bearings D are arranged so they do not interfere with the securing of the Master Car Builders' lid to the lug b, nor do they interfere with the opening and closing of this lid when it has been secured to the box. The usual leaf spring K is secured to the lid I and is adapted to bear upon the flat faces of the hinge lug b to hold the lid in its open and closed positions.

This journal box is thus adapted for use on cars and on all railroads where Master Car Builders' boxes are used as these rail-

roads always have in stock extra standard Master Car Builders' lids and, when it becomes necessary to place a new lid on the box, one of these Master Car Builders' lids can be used for this purpose, provided the repair man does not have at hand one of the lids which are constructed especially for this box.

We claim as our invention:

1. A journal box provided on its top between its sides with a lug, side bearing lugs arranged on said box at opposite sides of said other lug and in rear thereof, a lid having a hood portion which projects over said first mentioned lug and has laterally projecting trunnions at its sides which are journaled in said bearing lugs, and a spring member which exerts pressure on said lid for yieldingly resisting the movements of said lid. 75

2. A journal box provided on its top between its sides with a central lug, bearing lugs which are arranged on said box at opposite sides of said central lug and have rearwardly opening trunnion slots, a lid 90 having a hood portion which projects over said central lug and has trunnions which are journaled in said trunnion slots, and a spring member which acts to retain said trunnions in said slots and yieldingly resists the movements of said lid. 95

3. A journal box provided on its top at opposite sides thereof with bearings, a lid having trunnions which are journaled in said bearings, leaf springs which are arranged on said top between said bearings and beneath overlying parts of the lid and yieldingly resist the movement of said lid, and means located between said springs which hold the springs from lateral displacement. 100

4. A journal box provided on its top between its sides with a lug, bearings arranged on said box at opposite sides of said lug, a lid having projections which extend rearwardly between said lug and said bearings and are provided with side trunnions which are journaled in said bearings, and springs which are located on the top of said box beneath and act against said lid 115 projections. 110

5. A journal box provided on its top between its sides with a lug, bearings arranged on said box at opposite sides of said lug, a lid having trunnions at its side portions which are journaled in said bearings, cam projections on said lid which are located at the inner sides of said bearings, and leaf springs which are secured to the top of said box and are located beneath said cam projections and have portions that substantially conform to the path described by said cams when the lid is swung on its trunnions. 120

6. A journal box provided at the side portions of its top with bearings, a lid hav- 130

ing trunnions at its side portions which are journaled in said bearings, and leaf springs secured to the top of said box and having inclined bearing faces, said lid being provided at its upper edge with cam projections which extend rearwardly over said springs and against which said springs bear for holding said lid in its open and closed positions, said cam projections being arranged to afford a greater leverage to said

springs on said lid when the latter is in its closed position than when in its open position.

Witness our hands this 15th day of June, 1912.
